LE GRAND KNIFFEN, OF ROCHESTER, PENNSYLVANIA.

Letters Patent No. 87,500, dated March 2, 1869.

IMPROVED BUCKLE FOR GRAIN-BANDS, BAG-TIES, &c.

The Schedule referred to in these Letters Patent and making part of the same.

To all whom it may concern:

Be it known that I, LE GRAND KNIFFEN, of Rochester, in the county of Beaver, and State of Pennsylvania, have invented a new and useful Improvement in Buckles for Grain-Bands, Bag-Ties, and other purposes, of which the following is a full, clear, and exact description.

My invention consists—

First, in making an opening in the frame of the buckle, for the insertion of the cord or strap laterally, instead of threading it through the buckle, as heretofore.

Second, in a novel method of constructing the buckle of two separate sections, held together by the band or strap.

In the accompanying drawings—

Figure 1 represents a view in perspective of my improved buckle, as it appears when the cord or strap is locked.

Figure 2 represents a similar view of the body or frame of the buckle detached.

Figure 3 represents a vertical longitudinal section through the buckle.

The buckle is made, preferably, of cast-metal, in the form shown in the drawings.

The tongue *a* has an eye, *b*, in it, for the insertion

of the cord or strap *c*, and two lugs, *d*, which fit into open sockets, *e*, on the body or frame *f*.

The cord passes down within the buckle, as shown in fig. 1, and through an eye, *h*, on the frame.

It is then wound around the bundle or bag, and inserted laterally into the buckle, through the opening *i* in the frame, and is clamped between the beak of the tongue and the front bar of the buckle.

By this mode of construction, facility of manipulation is combined with efficiency in operation, and cheapness in manufacturing.

What I claim as my invention, and desire to secure by Letters Patent, is—

1. The buckle, constructed as set forth, with an opening in the frame, for the insertion laterally of the cord.

2. The combination of the body and tongue, with the binding-cord passing through both, substantially as set forth.

In testimony whereof, I have hereunto subscribed my name.

Witnesses: LE GRAND KNIFFEN.

EDWARD KELLER,

J. D. EDMOND.
